The ornamental design for a handle for a saw, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a rear perspective view of a handle for a saw according to our new design, showing a solid rendering thereof having a contrast as between the component parts, as indicated by relative shading;

FIG. 2 is a left side view of FIG. 1;

FIG. 3 is a front perspective view of FIG. 1;

FIG. 4 is a right view of FIG. 1;

FIG. 5 is a bottom plan view of FIG. 1;

FIG. 6 is a top plan view of FIG. 1; and,

FIG. 7 is a front end view of FIG. 1.

The broken line showing of the bolt forms no part of the claimed design. The dash-dash broken lines illustrate environmental structure and form no part of the claimed design.
